COMBINED CARBURETOR AND FUME ELIMINATOR INNERLOCK FOR INTERNAL COMBUSTION ENGINES

Edward G. Parvin, Roselle, N. J., assignor to National Pneumatic Company, New York, N. Y., a corporation of West Virginia

Application November 17, 1938, Serial No. 240,948

10 Claims. (Cl. 123—124)

This invention relates to improvements in so-called fume eliminators as applied to internal combustion engines used particularly on heavy vehicles for the purposes of eliminating fuming and gassing thereof and maintaining the engine cool.

Speaking generally, a device of this nature automatically operates when the carburetor throttle valve, and of course the accelerator pedal 10 are at idling position, or are moved towards idling position and the engine is running at greater than idling speed, to open the intake manifold of an internal combustion engine directly to the atmosphere so as to by-pass the carburetor and supply fresh air directly to the cylinders. A device of this nature is disclosed in my copending application Serial No. 186,280, filed January 22, 1938, Patent No. 2,148,709, issued February 2, 1939.

In the actual use of a device such as disclosed in my above mentioned copending application it has been found that the operation of such systems can be improved by providing a lock for the economizer and accelerating piston assembly 25 of the carburetor to prevent the loss of the accelerating charge during the time of fresh air supply and the consequent spitting and backfiring of the engine subsequent thereto upon acceleration because of the loss of that charge. The nature of this improvement will be apparent 30 from the following description of the operation of the invention provided subsequent to a description of the structure of a complete system in accordance therewith.

This invention resides substantially in the combination, construction, arrangement and relative location of parts, all as will be set forth in full detail below.

Referring to the drawings,

Figure 1 is a partly diagrammatic side elevational view of a system in accordance with this invention applied to the intake manifold of an internal combustion engine;

Fig. 2 is a vertical, central, longitudinal, cross-sectional view through the fume eliminator portion of the mechanism;

Fig. 3 is a cross-sectional view partly in plan taken on the line 3—3 of Fig. 2;

Fig. 4 is a vertical, cross-sectional view 50 through the economizer and accelerating piston assembly of a carburetor showing the lock of this invention applied thereto;

Fig. 5 is a horizontal, longitudinal, cross-sectional view through the lock cylinder showing 55 a portion only of the carburetor;

Fig. 6 is a diagrammatic view of a modified arrangement for locking the economizer and accelerating piston assembly in closed position; and

Fig. 7 is a longitudinal, central, cross-sectional view through one of the check valves of the carburetor.

As illustrated in Figure 1 the intake manifold of an internal combustion engine is designated by the reference numeral 1. Mounted thereon in accordance with common practice is a carburetor 2 provided with an air inlet strainer 3. The carburetor as illustrated is of the down draft type. At 4 is the carburetor throttle valve shaft to which is secured a lever 5 extending radially therefrom in both directions. The lower end of lever 5 is pivotally connected by a link 6 to a bell crank 7 pivotally mounted on a shaft 8 below the floor board of the vehicle and in turn connected by a link 9 to the accelerator pedal 10 mounted on the floor board. The other end of lever 5 is pivotally connected by link 11 to an arm 12 on a shaft 13 which operates mechanism to be described in detail later. At 14 is shown the air inlet valve which is mounted on the intake manifold 1 by means of a suitable coupling fixture 1b. At 17 is a housing for the remainder of the mechanism which will be described in detail later, while at 18 is shown the pressure fluid supply pipe to a control valve within the housing 17. At 19 is a housing for a bellows member which 20 operates the control valve as will be explained in detail below. The pipe 20 extends from the control valve to the pneumatic lock mounted on the carburetor and not shown in Figure 1.

Referring to Fig. 2 there will be seen in cross-section all the mechanism comprising and associated with the air inlet valve 14, the bellows mechanism, and the pressure fluid supply control valve. In this figure a portion of the intake manifold is shown at 1 provided with an air inlet opening 1a in alignment with an opening in the coupling fixture 1b. Mounted on the coupling fixture is the air inlet valve 14 comprising a housing 21 formed to provide a cylinder in which a piston 22 is mounted for sliding movement vertically. The piston is hollow as shown and within it is a valve stem 25 on the upper end of which is secured a seat 24 for a spring 23 which lies between it and the lower end of the cylinder. On the lower end of the valve stem 25 is a valve 26 arranged to rest on a seat 27 and close the passage through the seat from the air inlet opening 28. The casing 21 is formed so as to have the extension housing 16 on which the strainer 15 is mounted as shown.

At 29 is a passage in the portion 17 of the housing opening into the cylinder 21. Mounted on the bottom wall of the portion 17 of the housing is the pressure fluid control valve comprising a housing 30 having a longitudinal bore therethrough of various diameters as shown. The outer larger end of the bore is closed by a cap screw 31 and the bore is divided into several chambers by means of the apertured plugs 32 and 33. Extending through the apertured plugs of the valve housing is a valve stem 38 which has a pair of opposed valves 34 and 35 thereon arranged to cooperate with seats on the plugs 32 and 33 respectively. The space to the right of plug 32 is open to the atmosphere through the exhaust passage 37. The space between the plugs 32 and 33 is connected by a passage in the valve casing 30 which forms a continuation of the passage 29 in the cylinder 21. The space between these plugs is also open through a passage 20' (see also Fig. 3) into which one end of the pipe 20 extends. The space between the screw cap 31 and the plug 33 is in communication with a threaded passage 18' to which one end of the pressure fluid supply pipe 18 is connected. A spring 36 is provided engaging the valve stem 38 to hold it in the position shown so that valve 35 is seated and valve 34 is unseated.

The right hand end of the valve stem 38 projects out of the end of the casing 30 and engages a lever 39 pivotally mounted at its upper end at 40 on the casing 30. This lever extends down into the air inlet casing 16 and has threaded mounted thereon a stud 41 provided with a disc 42. A tightening screw 44 is provided to lock the stud 41 in adjusted positions. The interior of the inlet casing 60 is shaped as indicated at 43 to provide a converging construction adjacent the end of the casing supplying air to the valve 26. It will be noted that the further the disc 42 moves to the left in the converging direction of the portion 43 the more it closes it off. When it is at its extreme left hand position it most nearly closes it off, but it is to be noted it never completely closes this passage. The reason for this will be described later, although it is set forth in full detail in the above entitled application.

At 45 is a spring interposed between the housing and the lever 39 to urge it towards the position shown in Fig. 2. At 46 is a short lever secured to the shaft 18 within the housing and provided with a projection 48 adapted to engage the lever 39 which action is insured by a spring 47.

Referring now to Figs. 2 and 3 there is shown at 49 a bar which extends between and is connected to a pair of rods 50. This bar 49 extends transversely of the lever 39 as shown. The rods 50 extend into the housing 19 through passages as shown in Fig. 2, which permit unrestricted longitudinal movement thereof. These rods are connected to a disc 51 which in turn is connected to and forms a seal with a bellows 52. The other end of the bellows is clamped between the housing 19 and a cap 53 so that the space within the bellows, in conjunction with the disc 51 and cap 53, is a closed or sealed chamber. Fixedly mounted on the disc 51 at its center is a rod 54 which is encircled by a spring 55 lying between the end wall of the casing 19 and a washer 56 held on the rod 54 by a nut as shown.

Extending upwardly through the wall of the cylinder 21 is a passage 57 which communicates with a longitudinally extending passage 58 in the portions 17 and 19 of the housing. The pas-

sage 58 terminates in a port 59 in the cap 53 thereby opening into the chamber formed by the bellows.

Referring to Figs. 4 and 5 a portion of a carburetor having a vacuum actuated economizer and accelerating piston assembly is shown, also showing the pneumatic lock therefor in accordance with this invention. The portion of the carburetor illustrated is that of a down draft carburetor which is shown having the usual fuel chamber 60. This chamber is in communication with a smaller chamber 64 in the carburetor wall through a check valve 61 in accordance with well known practice. Mounted in the bottom of chamber 64 is another valve frequently called an economizer valve which is in communication with the power and accelerating jet 63 of the carburetor. At 65 is a piston mounted for sliding movement in the chamber 64 and engaged by a spring which is shown in its compressed state so that it is tending to move the piston 65 downward. Connected to the piston is a piston rod 66 which terminates in another piston 67 at the upper end of the chamber 64. The other end of this chamber is in communication at the passages 68, 70 and 71 with the mixing chamber of the carburetor. The space between the passages 65 and 67 is open to the mixing chamber of the carburetor through a passage 72.

The check valve 61 is shown enlarged in Figure 7. The passage 61' which it controls is enlarged at its left hand end as shown and internally threaded to receive a plug 61" which has a passage 61' therethrough. A valve member 61' is mounted in the little chamber thus formed and is provided with a spring 61' to hold it against the inner face of the plug 61" to seal the passage 61' therethrough. The valve disc 61' is provided with a guiding tail piece 61" which in cross-section is in the form of a spider web or cross or as to cross-position the valve disc without interfering with the flow of gasoline therearound. When the piston 65 moves upwardly a suction condition is created below it, causing the valve 61' to open so that gasoline may flow into the chamber 64. When the piston 65 descends the gasoline in the chamber 64 may not escape because the spring 61' holds the valve 61' so as to close the passage 61' and of course in addition the gasoline will help to create a pressure to hold it seated.

Mounted on the fuel supply chamber 60 is a pneumatic lock comprising a cylinder 73 with a closure cap 72 having a threaded inlet passage 20" to which the other end of the pipe 20 is connected. Within the cylinder 73 is a piston 75 which is engaged by a spring 76 to hold it in the position shown in Fig. 5 when there is no pressure in the cylinder. The piston is provided with a piston rod which extends through the end of the cylinder 73 and is provided with a reduced portion 74 which moves in a passage in the wall of chamber 64 of the carburetor. It will be seen that the reduced portion 74 may be projected into the chamber 64 when pressure is applied to the piston 75 so as to engage under the enlarged head 65 of the piston 67 to hold it in its uppermost position against the action of spring 68, as will be described at the proper place.

The operation of the system will be first briefly described without reference to the innerlock feature of the invention. If it be assumed that a vehicle driven by an internal combustion engine with the invention herein disclosed attached is operating say at 40 miles an hour and the operator removes his foot from the accelerator pedal 75

10, it will be seen that in accordance with usual practice the carburetor throttle valve will move back to fully closed position. At this time the engine will be simply receiving an idling mixture. If the clutch is left engaged it is apparent 5 that the vehicle will be driving the engine at a speed greater than idling speed. Under these conditions it is the basic purpose of a system of this type to by-pass the carburetor and supply 10 adequate quantities of fresh air directly into the intake manifold so that the engine is pumping non-explosive, substantially atmospheric air. At the same time, referring to Fig. 2, the link 11 will rotate lever 46 through shaft 13 away from the 15 arm 39, leaving it free thereof and compressing spring 47. Under idling conditions, that is where the fuel mixture supply is reduced to an idling quantity, the pressure in the intake manifold 1 will fall with the result that the pressure in passages 59 and 58 and the chamber formed by the 20 bellows 52 will also fall to substantially the same value. As the space around the bellows 52 within chamber 19 is open to the atmosphere through the passages around the rods 58 and 54 (the portion 25 17 of the casing not being sealed as shown for example in Fig. 2 where the closure plate 17* does not fit tightly around the tubular extension forming the casing for the passage 18'), the bellows 52 will contract moving plate 51 to the left, Fig. 2. 30 Since the rods 50 are connected to this plate they likewise move to the left as does rod 54, compressing the spring 55. The bar 49 is carried to the left with rods 50, thereby moving the lever 39 in a clockwise direction. This movement of 35 the lever compresses spring 54 and moves the valve stem 38 to the left unseating valve 35 and seating valve 34. The unseating of valve 35 connects the pressure fluid supply source through pipe 18 with the cylinder 21 through the passage 28. The rise in pressure in the cylinder moves 40 the piston 22 down compressing spring 23 and opening valve 26. In view of the reduced pressure conditions within the intake manifold 1 it is apparent that air will rush through the strainer 15, the casing 16, passage 28, passed valve 26 into the intake manifold through an opening 1*. Thus the cylinders get fresh air directly through this route, by-passing the carburetor and reducing 45 what mixture comes from it to a non-explosive mixture.

50 It will be noted that the clockwise movement of lever 39 has moved the disc 42 towards the smaller end of the portion 43 of the air inlet passage so that the air rushing passed the disc 42 around the edges thereof creates a pressure thereon which tends to hold the lever 39 in this new position. These conditions continue to exist while the vehicle speed falls until it approaches substantially idling speed. Of course as the engine 55 speed falls the quantity of air, and hence its rate of movement passed the disc 42 into the intake manifold gradually falls. At the same time the pressure in the intake manifold gradually rises, and as a result the pressure in the bellows 52 gradually rises so that the bellows expands moving bar 49 towards the right away from the actuated lever 39. At just about idling speed for the engine the parts being proportioned and spring 45 having been properly selected, the lever 39 will 60 move back to the position shown in Fig. 2. In other words, whatever pressure is created by the air rushing in passed the disc 42 at reduced speed, is not sufficient to hold the lever in its actuated position against the resistance of spring 45.

75 The return of lever 39 to the position shown in

Fig. 2 releases the valve stem 38 so that the spring 36 can move it back to the right seating valve 35 and unseating valve 34. The seating of valve 35 cuts off the supply of air to the cylinder 21 and opens it to exhaust through plug 32 and exhaust passage 37. Thus spring 23 snaps valve 26 onto its seat and cuts off the supply of air through the housing 16. The engine is now back in its normal condition getting the idling mixture from the carburetor and it therefore resumes 10 its normal operation. It will be apparent that if after the throttle is at idling position but the speed has not yet fallen to idling speed, the operator should depress the accelerator pedal 10, it is of course necessary to close valve 26 so that the 15 engine can operate normally. This is a very frequent condition on the road and to insure that the valve 26 is immediately closed the lever 46 is provided to push the lever 39 back to the position shown in Fig. 2, without any time lag. This 20 occurs of course because of the connecting link 11.

In the operation of a system of this type where the carburetor employed is of the type which employs a suction operated economizer and accelerating piston assembly as herein disclosed it has 25 been found, as will be obvious, that at the time valve 26 is open the pressure in the intake manifold and in the carburetor falls substantially to atmospheric pressure so that the vacuum condition within the carburetor is not high enough 30 to hold the piston 67 in the position shown in Fig. 4. The result is that it falls down, opening valve 62 and permitting the discharge of a portion if not all of the accelerating charge of gasoline in the chamber 64 below the piston 65, through the 35 jet 63. Then when the accelerating pedal is depressed and the carburetor throttle valve thereby opened for acceleration, there is no accelerating charge of gasoline available to meet the carburetor demand. Modern automobile engines are 40 so designed today as to depend upon this accelerating charge and hence when a system as described above is applied to an engine having a suction operated assembly of this type, the engine tends to spit when the throttle valve is opened 45 from idling position, and in addition it does not produce the power that it should. Furthermore, it will be apparent that the accelerating charge of gasoline is lost by this action which of course represents a waste, which is undesirable. 50

For this reason the latch or lug 74 is provided with the piston 75 in the cylinder 73 to move it into locking position at the time the previously described mechanism operates to open valve 26. Thus every time valve 34 seats and 55 valve 35 unseats to supply air to the cylinder 21 air is also supplied through the port 20' (Fig. 2) and pipe 20 (Fig. 1) to move the piston 75 (Fig. 5), to the right so that the latch or lug 74 moves under the rim of the enlarged upper end of the 60 piston 67 (see Fig. 4). The result is then that when the pressure falls in the carburetor as it will when valve 26 is open, the pressure will also fall in passages 71, 70 and 69, but the piston assembly cannot be moved down by spring 68 65 because it is held by the latch 74. Thus the accelerating charge in the chamber 64 remains there and is available when the accelerating pedal is depressed to perform its intended function. It is hardly necessary to point out, as the portion 70 of the carburetor illustrated in Fig. 4 is well known in the art, that the check valve 61 merely permits the flow of gasoline from the chamber 60 into the chamber 64 when the piston assembly 67 moves up so as to fill the chamber 64. At this 75

time of course valve 62 is closed. When the piston assembly 67 moves down at the time of acceleration check valve 61 closes so that the fuel in chamber 64 cannot be forced back into chamber 66. The result is that valve 62 opens and the charge is fed through the jet 63 into the carburetor.

It is of course apparent to those skilled in the art that the details of this invention may be widely modified. For example, instead of locking the piston 67 in its closed position by means of a directly acting pneumatic lock, various forms of electro-magnetic locks can be employed. For example there is shown one form of electro-magnetic lock in Fig. 6. In this case the piston 67 is provided with an extension 100 of magnetizable metal such as iron to form the movable core of a solenoid winding 101. This winding is in circuit with a suitable current source 102, and a switch including a movable contact 14'. This contact is mounted on the piston rod 74. This provides an air operated switch in which the cylinder 73 with its piston and pressure fluid supply pipe 20 is of exactly the same construction as the arrangement previously described and illustrated for example in Fig. 5. In other words, instead of the piston rod 74 forming a latch for direct cooperation with the piston 67 it is made part of a switch. The pipe 20 is connected as in the previous arrangement so that fluid pressure is supplied to the cylinder 73 at the same time as it is supplied to the cylinder 21. Thus every time the valve 26 opens the switch 14' closes completing the circuit to the winding 101 and holding the piston 67 in its seated position so as to hold it and the parts connected thereto in the position shown in Fig. 4.

From the above description it will be apparent to those skilled in the art that this invention may be embodied in other physical forms without departure from the novel subject matter herein disclosed. I do not, therefore, desire to be strictly limited to the disclosure as given for purposes of illustration, but rather to the scope of the appended claims.

What I seek to secure by United States Letters Patent is:

1. In a system of the type described the combination with the intake manifold of an internal combustion engine and a carburetor connected thereto having a vacuum operated economizer and accelerating piston assembly therein, of means for simultaneously introducing fresh air directly into the intake manifold of the engine 50 when the throttle valve of the carburetor is at or moved towards idling position and the engine is operating at greater than idling speed, and locking the economizer and accelerating piston assembly of the carburetor against movement.

2. In a system of the type described the combination comprising the intake manifold of an internal combustion engine, a carburetor connected thereto having a throttle valve and a vacuum lifted accelerating piston assembly, valve means for supplying fresh air directly to the intake manifold, means for opening said valve when the throttle valve of the carburetor is at idling position and the engine is operating at greater than idling speed, and means for holding the accelerating piston assembly in the vacuum lifted position while said valve means is open.

3. The combination with the intake manifold of an internal combustion engine, a carburetor having a throttle valve connected thereto and a valve for supplying air directly into the intake

manifold, of means controlled by the pressure conditions in the intake manifold for operating said valve, means in the air stream to said valve for holding said last mentioned means actuated until the speed of the engine approaches idling speed, and means actuated with the throttle valve of the carburetor for moving said last means to release said first means when the throttle valve is opened.

4. The combination with the intake manifold 10 of an internal combustion engine, a carburetor connected thereto having a throttle valve and a valve for supplying air directly into the intake manifold, of pressure fluid actuated means connected to the intake manifold for operating said 15 air inlet valve, means controlled by the movement of air to the intake manifold for maintaining said last mentioned means actuated until the engine speed approaches idling position, and means actuated with the throttle valve of the 20 carburetor for moving said last means to release the fluid pressure actuated means when the throttle is opened from any position.

5. The combination with the intake manifold 25 of an internal combustion engine, a carburetor connected thereto having a throttle valve, accelerator means for operating said throttle valve, and a pressure fluid operated inlet valve for controlling the supply of fluid under pressure to an exhaust from said inlet valve, of pressure fluid 30 operated means connected to the intake manifold for operating said valve, means in the stream of air supplied to the manifold through the inlet valve for holding said air valve operated until the engine speed falls to idling speed, or to speed 35 corresponding to a retarded position of the carburetor throttle valve, and means also actuated by said carburetor means for returning said last mentioned means to inoperative position upon movement of the throttle valve from any position 40 to a more open position.

6. The combination with the intake manifold of an internal combustion engine and a valve for supplying air thereto, of means controlled jointly by the pressure conditions in the intake 45 manifold and the accelerator for opening said valve, means controlled by the flow of air to the intake manifold for maintaining the air inlet valve open until the engine speed falls substantially to idling speed, and manually operated 50 means for returning said last means to inoperative position.

7. The combination with the intake manifold of an internal combustion engine, a carburetor connected thereto having a throttle valve, actuating means for the throttle valve, and an air inlet valve for supplying air directly to the intake manifold, of means controlled by the pressure conditions in the intake manifold for opening said air inlet valve when the carburetor throttle valve 60 is returned to or moved towards idling position, means controlled by the flow of air to the intake manifold for holding said pressure controlled means actuated until the engine falls to a speed corresponding to the throttle opening, and means 65 for returning said last means to inoperative position immediately upon further opening of the throttle valve.

8. The combination with the intake manifold of an internal combustion engine, a carburetor 70 connected thereto having a throttle valve and a vacuum lifted accelerating valve operating means, actuating means for said throttle valve and an air inlet valve for supplying air directly to the intake manifold, of means controlled by the pressure 75

conditions in the intake manifold for opening said air inlet valve when said throttle valve is returned to or moved towards idling position, and means operated with said last means for locking said accelerating valve operating means in vacuum lifted position while said air inlet valve is open.

9. The combination with the intake manifold of an internal combustion engine, a carburetor connected thereto having a throttle valve and a vacuum lifted accelerating valve operator, actuating means for said throttle valve and an air inlet valve for supplying air directly to the intake manifold, of means controlled by the pressure conditions in the intake manifold for opening said air inlet valve when said throttle valve is returned to or moved towards idling position, means operated with said last means for locking said accelerating valve operator in vacuum lifted position, means controlled by the flow of air to the intake manifold for holding said previous means

actuated until the engine speed approaches idling position or a position corresponding to the throttle valve opening, and means actuated with said pressure controlled means for holding said accelerating valve operator in vacuum lifted position until the engine approaches idling speed.

10. The combination with the intake manifold of an internal combustion engine, a carburetor connected thereto having a throttle valve, actuating means for the throttle valve and an accelerating assembly including a fuel valve, said assembly being connected to the intake manifold so that the fuel valve is closed when the throttle valve is in idling position, of means for opening the intake manifold to the atmosphere when the throttle valve is at or moved toward idling position and the engine is operating at greater than idling speed and means for preventing the opening of the fuel valve when the intake manifold is open to the atmosphere.

EDWARD G. PARVIN.
